UNITED STATES PATENT OFFICE.

FREDERIC W. FORGUS, OF ST. LOUIS, MISSOURI, ASSIGNOR TO STEWART SCOTT, JR., OF ST. LOUIS, MISSOURI.

FOLDER-ENVELOP.

1,240,961.

Specification of Letters Patent. Patented Sept. 25, 1917.

Application filed October 30, 1915. Serial No. 58,925.

To all whom it may concern:

Be it known that I, FREDERIC W. FORGUS, a citizen of the United States, and residing at the city of St. Louis and State of Missouri, have invented a new and useful Folder-Envelop, of which the following is a specification.

This invention relates to folder envelopes, and it has particular reference to that type of envelopes in which the face of the envelop is provided with a window through which addressee's name on an inclosure is visible.

An object of the invention is to produce a folder envelop comprising a face portion provided with sealing flaps on three side edges thereof, and provided with a portion integral with the remaining side edge adapted to receive written or printed matter, including the name and address of the addressee, and capable of being folded against the inner side of the face portion to present the name and address of the addressee as they appear upon said folded portion so that they are plainly visible through a window in the face portion of the envelop.

In connection with the object stated, and other objects and advantages which will hereinafter appear, it is appropriate to state that it is preferable that the portion containing the written or printed matter be severable from the face of the envelop along the folded line, so that the written or printed portion may be readily detached and removed without the necessity of opening the envelop on any other side.

There are various other objects and advantages of the invention, all of which will be apparent from the following detailed description, reference being made to the accompanying drawings in which I have illustrated preferred embodiments of the invention, and in which—

Figure 1 is a view of the envelop blank, showing a portion thereof so formed and arranged that it is adapted to receive written or printed matter.

Fig. 2 is a view showing the portion which receives the written or printed matter folded in position for the flaps to be folded over and sealed.

Fig. 3 is a view of the back of the envelop after all of the parts have been folded and sealed.

Fig. 4 is a view of the face of the envelop showing the name and address of the ad-

dressee as the same appear upon the folded portion, visible through the window in the face of the envelop.

Fig. 5 is a perspective view of a portion of the closed envelop illustrating the small opening at the end for the reception of the envelop opener by which the written or printed portion is detached from the inclosing portions of the envelop.

Fig. 6 is a view of another form of envelop blank.

Fig. 7 is a view showing an envelop completed from the blank shown in Fig. 6.

Fig. 8 is a sectional view on a line such as 8—8 of Fig. 7.

While I have illustrated only two specific forms or embodiments of the invention it is obvious that there may be various other specific forms or embodiments without departing in the least from the spirit and principles of the invention. Therefore, it will be understood that in describing these specific forms I do not restrict the invention to such forms, but that the device will be produced in all of the various forms and embodiments which preference or necessity may require.

The invention as illustrated in Figs. 1 to 5, inclusive, is particularly designed for use for statements. As shown in these views of the drawings the face 1 of the envelop is provided with a window 2, which may be either an open window or a window formed by rendering a portion of the face of the envelop transparent. One edge of the face 90

of the envelop is integrally united with a portion 3 having a space 4 adapted to receive a designation of the name and address of the user, and having designated spaces 5

adapted to receive the name and address of the addressee. The portion 3 is of such length that there is sufficient space below the name and address of the addressee for the reception of any desired written or printed matter.

The portion 3 is adapted to be folded along the line 6, which defines said portion 3 with respect to and from the face of the envelop, and when so folded after the written or printed matter has been placed

thereon the name and address of the addressee are visible through the window 2, thus serving as the address to which the package is to be delivered. Thus it will be

understood that the window 2 and the designated spaces 5 which receive the name and

address of the addressee are approximately at equal distances from the folded line 6, so that no particular attention is required in folding and closing the envelop aside from 5 effecting the folding approximately along the proper fold line. Obviously the envelopes may be constructed with the portions 3 of any required length so that envelopes may be provided for use as bills, notices, printed 10 matter in various forms, return postals, statements, letters and for any other purpose.

The face portion 1 of the envelop is provided also with integral end flaps 7 adapted 15 to be folded against the portion 3 after the latter has been folded upon itself and against the face of the envelop. The edge of the envelop which is opposite from the extended portion 3 is formed with an integral flap 8 20 adapted to fold upon the folded portion 3 and against the outer surface of the end flaps 7 after the latter have been folded against said portion. A quantity of adhesive material 9 is on the inner face of the 25 flap 8 which rests upon the end flaps 7, but the adhesive substance does not extend along the side edge of the flap 8 which is between the end flaps 7. In this way the flap 8 may be sealed or secured to the end 30 flaps 7 so as to complete the envelop. When the parts are thus folded it is possible to withdraw the folded portion 3 for the purpose of inspection, or for any other required purpose, without injury to the folded portion 35 containing the written or printed matter.

As shown it is preferable that the fold and severance line 6 be a slight distance from the starting points of the end flaps 7, so that when the envelop is closed there remains a 40 space 10 (Fig. 5), in which an envelop opener or paper cutter may be inserted to sever the folded portion 3 from the envelop, thus enabling said folded portion to be withdrawn. When the portion 3 is folded within 45 the envelop there remains visible a space on the back of said portion 3 adapted to receive a printed instruction or direction 11 to detach the folded portion from the remaining portion of the envelop by severing the 50 same along the line 6. Also the visible surface of the back of the portion 3 may be provided with a printed pointer or indicator 12 to direct attention to the open space 10, so that the person receiving the envelop will 55 have proper and accurate directions.

In the envelop illustrated in Figs. 1 to 5, inclusive, the portion 3 is designed to have a single fold between the line 6 and the lower edge of said portion. Obviously, 60 however, the scope of the invention is not restricted to an envelop in which the extended portion is capable of a single fold, for the extended portion may be of any desired length and capable of being folded 65 a number of times.

In Figs. 6, 7 and 8 I have illustrated the envelop provided with an extended portion arranged to receive printed or written matter and adapted to be folded a number of times. The envelop so constructed includes 70 a face portion 13 having a window 14, and provided with an extended portion 15 designed to receive the written or printed matter. The extended portion 15 has a space 16 adjacent to the upper edge thereof 75 for receiving a designation of the name of the user of the envelop, in the form of a letter head or otherwise. A perforated fold and severance line 17 extends along the line of union between the face portion 13 and the extended portion 15. Designated spaces 18 80 for receiving the name and address of the addressee are on the extended portion 15 at a suitable distance from the fold and severance line 17, so that when said portion 85 15 is folded against the face portion of the envelop the name and address of the addressee as the same appear upon the extended portion 15 will be visible through the window 14 and serve as the address for the 90 envelop. The portion 15 is of such length that it is capable of a number of folds, being substantially of the usual letter sheet size. After the extended portion 15 is folded against the inner surface of the face portion 95 of the envelop, the end flaps 19 are folded against said portion 15, and the side flap 20 is then folded to close the envelop and is secured to the end flaps by adhesive material 21. In this form of envelop the flap 20 is 100 preferably of only slightly less width than the face portion of the envelop, so that when the envelop is closed all of the folds of the extended portion 15 will be embraced between the front and rear portions of the 105 envelop, thus protecting the written or printed matter thereon. In this embodiment, as in the embodiment first described, the fold and severance line 17 is a slight 110 distance from the edges of the end flaps 19, as shown at 22, so that a suitable implement may be inserted to sever or detach the written or printed portion 15 from the face portion 13 of the envelop.

The envelopes may be produced in any desired dimensions so as to conform to commercial necessities and requirements, and to individual preferences. When the device is of any of the usual commercial sizes it may readily be inserted in a typewriting machine so that the writing may be performed on the machine. In order to facilitate the insertion of the device into the machine the end flaps may, if desired or required by the size of the envelop, be folded against the 125 face portion 1. When placed in the machine the designated spaces or lines 5 serve as guides for placing the name and address of the addressee in proper position, so that when the communication portion of the en- 130

velop is folded the name and address of the addressee thereon will be visible through the window 2.

It is apparent that a device of this character is adapted to many uses and that it may be made for any of the purposes herein mentioned, as well as for various other purposes. Therefore, in describing the invention I do not restrict myself to identical features of construction or to the identical uses designated, but what I claim and desire to secure by Letters Patent of the United States is—

A folder envelop, comprising a face, a window in the face, end flaps in connection with the face having their lower edges terminating above the lower edge of the face and leaving openings between the lower edges of the end flaps and the lower edge of the face when the envelop is folded, a communication portion in connection with the lower edge of the face adapted to fold against the inner side of the face, a folding and severance line at the lower edge of the face below the lower edges of the end flaps defining the communication portion from the face, whereby when said communication portion is folded and the envelop is closed an opening is formed between the lower edge 30 of each end flap and the lower edge of the

face defined by said folding and severance line, a space on the communication portion adjacent to the severance line for receiving a letter-head or the like, designated spaces on the communication portion adapted to receive the name of the addressee in such position that when the communication portion is folded the name will be visible through the window, said designated spaces and said window being equi-distant from said severance line, the space on the communication portion below the designated spaces adapted to receive the communication, a side flap at the side edge of the face opposite from the communication portion of less width than the face, and means for securing the side flap in connection with the end flaps only and leaving the side flaps and end flaps disconnected from the communication portion so that the envelop below the end flaps 50 is open to enable the communication portion to be inspected or withdrawn.

In witness whereof I have signed this specification in the presence of two subscribing witnesses.

FREDERIC W. FORGUS.
